(57) **CLAIM**

I claim the ornamental design for the novelty greeting card, as shown.

DESCRIPTION

FIG. 1 is an isometric view from the front of a partially folded Christmas card of my new design;

FIG. 2 is an isometric view from the back of the partially folded card with an address to Santa Claus on the back portion thereof;

FIG. 3 is an elevation of one side of the unfolded card of the invention, namely the side containing a picture or likeness of Santa Claus;

FIG. 4 is an elevation of the opposite or reverse side of the unfolded card;

FIG. 5 is an isometric view from the front of an alternative Christmas card of my new design;

FIG. 6 is an isometric view from the back of the partially folded card with an address to Santa Claus on the back portion thereof;

FIG. 7 is an elevation of one side of the unfolded card of the invention, namely the side containing a picture or likeness of Santa Claus;

FIG. 8 is an elevation view of the opposite or reverse side of the unfolded card; and,

FIG. 9 is an isometric view of the partially open card from the Santa Claus and Wish List side showing the bottom of the card still folded up with the Christmas message exposed as would first be seen by someone opening the card.
